Thomas D. Kennedy
ATTORNEY.

UNITED STATES PATENT OFFICE.

CHARLES C. PHILLIPS, OF DETROIT, MICHIGAN.

TIMER BRUSH.

Application filed June 1, 1925. Serial No. 33,920.

My invention relates to a new and useful improvement in a timer brush, and has for its object, the provision of a timer brush, adapted for use with the ignition system of 5 automobiles and the like, wherein the brush portion is afforded a sufficient contact with the shaft upon which mounted.

Another object of the invention is the provision of a timer brush mounted on a sleeve 10 carried by a rotating shaft and so arranged and constructed and mounted on said sleeve, as to maintain said sleeve in close connection, at all times, to provide an efficient conductor from said shaft to said brush.

Another object of the invention is the provision of a timer brush of the class described, having means for retaining the brush portion in outwardly extended position, relatively to the shaft upon which mounted, and 20 for affording a means of electrically connecting the brush to said shaft.

Another object of the invention is the provision of a timer brush having a sleeve adapted for mounting on a shaft and provided with resilient means for maintaining the brush in outwardly extending position, relatively to said sleeve, and for projecting through said sleeve, and contacting with said shaft, for establishing an efficient electrical connection between said brush and 30 said shaft.

Other objects will appear hereinafter.

The invention consists in the combination and arrangement of parts hereinafter described and claimed.

The invention will be best understood from a reference to the accompanying drawings, which form a part of this specification, and in which:—

40 Fig. 1 is a top plan view of the invention, applied to a timer shaft.

Fig. 2 is a sectional view taken on substantially line 2—2 of Fig. 1.

Fig. 3 is a side elevational view of the 45 invention.

Fig. 4 is a side elevational view of a modified form of the invention.

Fig. 5 is a sectional view taken on substantially line 5—5 of Fig. 3.

50 The invention is adapted for use with a timer, having a housing 9 provided with the terminals 10, which are electrically connected with the brush contacts on the inner surface of the housing 9. A shaft 11, is projected through the housing and used for rotating the timer brush in the customary 55

manner. Mounted on the shaft 11 and suitably keyed to rotate therewith is a sleeve 12 having a peripheral slot 13 formed therein. Projecting outwardly from the sleeve 12 and preferably made integral therewith are knuckles 14, which are spaced apart and adapted for receiving knuckles 15 formed on the brush arm 16. The sleeve 12 is preferably made from a stamping, the sleeve 12 and the knuckles 14 being struck from a single blank. However, this sleeve may also be formed from suitable cast metal if desired. The knuckles 15 are also integral with the arm 16, these knuckles and this arm being struck from a single blank. Projecting from one side of the knuckles 15 is a heel 17 of the arm 16. The end of the arm 16 is formed arcuate, as at 18, to provide a brush or contacting portion. A suitable pintle 19 is projected through the knuckles 14 and 15 to retain the arm 16 in pivotal relation to the sleeve 12. Coiled upon the pintle 19 is a spring wire 20, one 70 end 21 of which is adapted for engaging the arm 16 to retain the same in outwardly pressed position, relatively to the sleeve 12, so that the heel 17 is in engagement with the periphery of the sleeve 12. The opposite end 22 of the spring 20 is adapted to register with the slot 13, and to lie therein. The construction is such that when the sleeve 12 is positioned on the shaft 11, the end 22 of the spring will engage against the periphery of the shaft 11, this engagement being a 75 close one, resulting from the tension of the spring.

When the sleeve 12 is mounted on the shaft 11, and secured thereto, by the washer 24 and the nut 25, which are of conventional 80 construction, the spring 22 engaging against the shaft 11 will serve to retain the inner surface of the sleeve 12, which is diametrically opposite the slot 13 in close engagement with the periphery of the shaft 11, the end 22 of the spring serving as a lever to press the sleeve into close engagement with the periphery of said shaft 11. In this way, a direct connection is made between the shaft 11 and the arms 16, through the spring 100 20 and its ends 21 and 22. Consequently, irrespective as to the play between the sleeve 12 and the shaft 11, a contact for conducting electricity is always maintained between the sleeve 12 and the shaft 11, and between the arm 16 and the shaft 11. It will be noted 105 that in this structure, the connection be-

tween the arm 16 and the shaft 11 is a direct one, as the current is permitted to pass directly from the shaft 11 through the ends 22 and 21 of the spring 20, to the arms 16. 5 This construction is one which renders a connection of the highest degree of efficiency, and has proved most practical in actual operation. It will also be noted that if the shaft 11 does not run true in its journals 10 the connection between the arm 16 and this shaft 11 will still be maintained.

In Fig. 4, I have shown a modified form of the invention, in which the sleeve 12 is not provided with the peripheral slot 13. In 15 this form, the end 22 of the spring 20 engages against the periphery of the sleeve 12. When the contact portion 18 of the arm 16 is in engagement with the inner surface of the housing 9, so as to perform its function 20 as a brush, to establish the connections at periodic times, in accordance with the desired operation of the timer, the portion 22 of the spring will be under considerable tension, which will cause the sleeve 12 to be 25 pressed tightly against the periphery of the shaft 11, at one side, should there be any play between the sleeve and the shaft. In this connection, it will be noted that the arm 16, and the portion 22 of the spring, 30 together form a lever, which is fulcrumed on the pintle 19. This connection is also an efficient one, on account of the pressure between the various parts, resulting from the specific arrangement and structure of

the spring. The connection or contact is, 35 of course, not a direct one, as in the case of the preferred form, but because of the strain between the several parts, effects a result tantamount to a direct connection.

While I have illustrated and described the 40 preferred form of structure, I do not wish to limit myself to the precise details set forth, but desire to avail myself of such variations and modifications as come within the scope of the appended claim. 45

What I claim is:

A timer brush of the class described adapted for mounting on a rotatable shaft comprising a strip of metal curled to form an open knuckle, said open knuckle being 50 of size sufficient for the snug reception of said shaft, one end of said knuckle being radially outwardly turned and centrally notched to provide a pair of spaced tongues, each of said spaced tongues being curled to 55 form knuckles; a contact arm having tongues cut from its edges and curled to form knuckles for engaging between said first mentioned knuckles, one end of said arm being formed substantially semi-circular for providing a contacting surface and the other end projecting rearwardly for providing an abutment end; and resilient means for normally retaining said abutment end in engagement with said open knuckle. 60 65

In testimony whereof, I have signed the foregoing specification.

CHARLES C. PHILLIPS.
